UNITED STATES PATENT OFFICE

150,297

DESIGN FOR A SCRIBING TOOL

Roy A. Hutchinson, Columbus, Ohio

Application March 25, 1946, Serial No. 127,927

Term of patent 7 years

(Cl. D54—13)

To all whom it may concern:

Be it known that I, Roy A. Hutchinson, a citizen of the United States, residing at Columbus, in the county of Franklin and State of Ohio, have invented a new, original, and ornamental Design for a Scribing Tool, of which the following is a specification, reference being had to the accompanying drawing, forming a part thereof.

Fig. 1 is a perspective view of a scribing tool, showing my new design;

Fig. 2 is a side elevational view thereof;

Fig. 3 is a top plan view.

I claim:

The ornamental design for a scribing tool, as shown.

ROY A. HUTCHINSON.
